UNITED STATES PATENT OFFICE.

WILLIAM F. STONE, OF WOODBURY, NEW JERSEY, ASSIGNOR TO STAR SEAL COMPANY,
A CORPORATION OF NEW YORK.

BOTTLE-SEALING MACHINE.

1,037,359.

Specification of Letters Patent. Patented Sept. 3, 1912.

Application filed March 4, 1911. Serial No. 612,363.

To all whom it may concern:

Be it known that I, WILLIAM F. STONE, a citizen of the United States, and a resident of Woodbury, county of Gloucester, 5 and State of New Jersey, have invented certain new and useful Improvements in Bottle-Sealing Machines, of which the following is a full, clear, and exact specification.

The object of my invention is to provide 10 mechanism for seating a seal in centralized position within the neck of a bottle especially formed for such seal, and to so conform the seal when seated to the shape given the neck that the two will be adequately secured together for the purposes 15 intended, all of which results being accomplished by a single relative movement of the bottle and sealing mechanism together.

My device as shown in the accompanying 20 drawings is distinct from any mechanical means for feeding the seals to it, and it will be described as receiving the seals by hand feeding.

A further object of my invention however is to so construct the parts that mechanical feeding of the seals may be provided, in which connection I have made a copending application showing my improved sealing device in conjunction with 25 my improved seal feeding machine.

The sealing device and bottle are intended to have relative motion to and from each other. The machine as shown is provided with a rigid stand for the bottle and means 30 for reciprocating the sealer to and from the bottle. The reverse of this can however be resorted to if desired and the sealer remain stationary and the bottle given the reciprocating motion to and from it. In 35 either instance the relative motion brings the plungers in contact with the bottle.

The plungers have suitably formed lower ends relatively positioned to operate at predetermined periods in the reciprocations of 40 the device to perform their respective functions in the sealing operation. The outer plungers are intended for centralizing and holding the bottle. Two such plungers are shown. They are the first to engage the 45 bottle and operate consecutively, the outer one first, to first centralize and then hold the bottle preparatory to sealing it.

The inner set of plungers is the reverse 50 of the outer ones. The innermost or central plunger is lowest in normal position and

the others consecutively higher. They move down as a unit and reach the bottle in the order as they are normally positioned but not until the outer plungers have operated. The outer plungers engage directly with the 60 bottle, while the inner group operates directly upon the seal. The inner plungers first seat the seal in proper position and then gradually press it in such close contact with its seat as will make an air tight connection and finally bend the intended parts of the seal (flange) to lock it in such compressed position. The reciprocating mechanism is preferably connected to the outer plunger. The working end of the plunger 65 is only intended to assist in centralizing a bottle that is considerably out of center. It is of sufficient diameter to then pass over and down the outside of the neck of the bottle. When the other plungers respectively reach the bottle their motion is arrested and further movement of the other plunger downward acts upon the plunger whose motion is arrested to compress a 70 spring behind it to cause a gradual increase of pressure of the plunger upon the bottle. The device operates then first to centralize the bottle; second to hold the bottle in this position; third, to bring the seal to its seat in the bottle; fourth, to press it to its 75 seat to make an air tight connection; fifth, to bring the seal forming plunger (or plungers consecutively) in contact with the seal, and sixth, to conform the seal to the recessed bottle by a continually increasing pressure 80 until the seal is securely locked in its compressed engagement with its seat to secure the required air tight fit.

In my device I have found it beneficial to employ two plungers for conforming the 85 seal. The outer plunger of the two is the last to act. It has upon its working end a circular shoulder which engages the upturned edge of the seal. It acts to prevent the seal from freely spreading outward as 90 it is being turned over along the edge and instead, confines it within the circumference of the shoulder, and compels the superfluous metal composing the flange of the seal to be crowded down in the circular groove 95 formed in the neck of the bottle to most effectively secure the seal in its compressed condition to its seat in the bottle. I am thus enabled by a simple downward movement of the plunger to give to the upturned 100

flange or edge of the seal a formation much as if a spreading tool exerting lateral pressure were used but without complicating my device with such additional means.

5 In my device I hold the seal in place by means of a split ring arranged within a groove formed on the cylindrical face of the seating plunger, the advantage of this construction will be more clearly seen as my 10 device is explained in detail.

Referring to the drawings forming a part of this specification, Figure 1 is an elevational view partly in section of my device with the respective parts in their normal positions. Fig. 2 is a sectional elevational view of the plungers in their respective final positions upon a sealed bottle, and Fig. 3 is a perspective view of a preferred type of seal for use with my device.

20 For the purpose of illustrating my invention I have preferred to show the device in its simplest form, that is to say, as a hand operated machine. My device, as is obvious, may be used with other power for driving 25 it, such, for instance, as belt and pulley driven by foot, steam, etc. but in such instances additional reciprocating mechanism would be needed.

A rigid stand or base 1 is provided for 30 supporting the bottle 2 preparatory to being sealed. This stand may conveniently be a bracket secured to a wall, post or other suitable place. To provide a yielding seat for the bottle to overcome any possible 35 shock caused by the descending plungers, the stand is provided with a rubber mat 3. A hollow post 4 is firmly secured in upright position to the base 1. The top of this post may also be secured to the general support (not shown) as by a bracket 5.

The post is for mounting the plungers upon. This is preferably accomplished by slidably mounting a sleeve 6 upon the post. The sleeve is secured to the outer plunger 45 by a web 7 and is cut away providing an opening 8 to facilitate the forming of a recess or chamber 9 in the web. A pinion 10 is mounted within this chamber upon the shaft 11. A rack 12 formed on the face of 50 post 4 is in mesh with the pinion. A hand wheel 13 is mounted on the shaft 11 for turning the pinion although other driving means may be employed if desired. By this mechanism the plunger as is obvious can 55 be moved up and down to and from the bottle. Compensating mechanism is provided for counterbalancing the weight of the plungers. This preferably comprises a weight 14 of cylindrical formation placed 60 within the hollow post and connected to the web of the plunger by a chain 15 extending over a pulley 16 mounted on bracket 17 secured at the top of the post.

The seal 18 shown in connection with 65 my device is intended to represent a type of

seal formed of a disk of metal 19 faced by a smaller disk 20 of yielding material as cork. The part of the metal disk extending beyond the facing disk is upturned and provided with a plurality of radial slits 70 forming thereby the serrated flange 21 composed of a plurality of independent members all radiating from the central body part. The bottle adapted for such a disk has formed within the neck a circular groove 22. The lower face of this groove forms a seat 23 for the yielding disk 20 and the groove itself forms a receptacle for the upwardly turned flange. 75

My method of sealing operates by simple pressure downward, to crimp the flange within the groove of the bottle and around the outside thereof to form of each section an independent spring clip, so to speak, engaged within the groove and exerting its force to assist in holding the yielding seal firmly upon its seat. The strength of the combined clips is sufficient to form the sealed joint. The strength of any one however is not so great but that it may be easily overcome by simply grasping the overturned end thereof and forcing it back toward the center of the seal to free the crimped part from engagement with the shoulder formed by the groove in the bottle. 95 No tool is needed for this as the sections of the flange are purposely made small enough to be disengaged by the fingers and when a sufficient number have been disengaged the seal can be easily dislodged from the bottle. It is not always necessary nor expedient to leave all the segments of the flange upon the seal, but advantage is gained by removing part of them therefrom, only leaving sufficient to provide 100 strength enough for the locking joint. The seal shown has but four of these segments intact.

The construction and arrangement of the concentric plungers are as follows: The outer plunger (or receptacle) 24 is preferably tubular in shape and opened at both ends. The lower end is formed with an upwardly converging interior rim 25 which is the first to contact with the bottle (if it be much out of center) to move it nearer its correct position below the seal. The rim is of sufficient diameter, as before remarked, to permit the neck of the bottle to pass entirely within it. It has the internal flange 26 formed thereon to afford a seat for the adjacent plunger 27. This plunger is the next to contact with the bottle and has at its lower end an upwardly converging interior rim 28, which in normal position is a continuation of the rim of the first plunger. This rim is of a diameter to engage the outer edge of the neck of the bottle. It first completes the centralizing of the bottle and then holds it firmly in that position during 135

the operation of the other plungers in seating and forming the seal.

The next plunger 29 is formed hollow and is closed at the top by an enlarged head 30 of a sufficient size to slidably fit within the outer plunger or receptacle. The body of the plunger is reduced in diameter to fit within the second plunger 27. The head 30 is a suitable distance above the plunger 27 to afford a chamber for the helical spring 31. The head rests in normal position against one or more lugs 32 formed on the plunger 24. The second and third plungers are placed in their respective positions 15 within the first plunger from the top thereof and to permit the second plunger to pass the lugs 32 grooves 33 are formed therein. The first plunger is preferably externally threaded to receive the correspondingly internally threaded cap 34 provided with a head 35 adapted to receive a wrench for turning it. Within the chamber formed between the cap and head 30 of the third plunger is a helical spring 36. This spring 20 is of sufficient strength to withstand the pressure of the other springs as they are compressed during the sealing operation. The lugs 32 which I provide for seating the plunger 29 in normal position enable the 25 spring 36 to be normally under compression without affecting the relative positions of the plungers or the tensions in the other springs, but providing the necessary resistance to complete the sealing operation. The 30 working end 37 of this plunger has the shoulder 38 formed therein for receiving the upturned edge of the seal flange and to confine it as has already been described. This plunger is the last to act and is accordingly the highest in position.

The next plunger 39 is mounted within the plunger 29 and has a working lower end normally below the end of that plunger. It is the first to begin forming the flange of 45 the seal. The working end of this plunger is formed with an upwardly diverging face. This provides pressure upon the edge of the flange to force it downward in the groove of the bottle and at the same time to cause it 50 to spread outward. The plunger is secured in proper normal position preferably by a pin 40 extending through the stem of the plunger and having its ends projecting in the slots 41—41 formed in the plunger 29 to 55 permit the required relative motion. Above the plunger 39 is a spring 42 for affording the necessary resistance. The lower end of the plunger is preferably enlarged forming a shoulder 43. This fits within a corresponding enlargement formed in the 60 plunger 29 affording a seat 44 for the plunger 39 which together with the pin 40 and slots 41 limit the relative movement of the two plungers.

65 The plunger 39 has its lower end formed

hollow for a suitable distance upwardly to receive another plunger 45. This plunger has an enlarged lower end which is received by a correspondingly enlarged opening in the plunger 39 which provides a seat for the plunger 45 to restrict its movement into plunger 39. The plunger 45 is retained in normal position by the screw 46 passed through the plunger and screwed tight into the plunger 39. A spring 47 is mounted on the screw behind the plunger 45 to provide the required resistance. The plunger 45 is for receiving the seal and for carrying it down upon its seat in the bottle and for compressing it there. This plunger is 70 formed with a groove 48 in which is seated a split ring 49. This ring projects normally beyond the face of the plunger, and engages in spring-pressed engagement with a seal when slipped over it. This ring has 75 the advantage that it securely holds the seal in place upon the plunger until it is well upon its seat in the bottle. This insures a positive centralizing of the seal on its seat. My manner of holding the seal, as before 80 remarked, holds it firmly to the seating plunger until well down upon the bottle seat. The serrated flange on the seal is 85 preferably formed slightly flaring and this makes it admirably adapted to be slipped over my split ring.

Having thus described my invention I claim—

1. A machine for applying flanged seals to interior grooved bottles, comprising a 100 tool, for conforming the seal flange to the groove, having a working face adapted to engage the edge of the flange to confine its circumference, an end below said face having a face for supporting the flange from 105 the inner side thereof, and means for pressing the flange and said first face together to form the joint within the groove.

2. A machine for applying flanged seals to interior grooved bottles, comprising a 110 tool, for conforming the seal flange to the groove, having a working face adapted to engage the edge of the flange to confine its circumference, an end below said face having a face for supporting the flange from 115 the inner side thereof, means for holding the seal on said lower end, and means for pressing the flange and said first face together to form the joint within the groove.

3. A machine for applying flanged seals to interior grooved bottles, comprising a 120 tool, for conforming the seal flange to the groove, having a working face adapted to engage the edge of the seal flange, a flange on said face for confining the circumference 125 of the seal flange, an end below said face having a face for supporting the seal flange from the inner side thereof, and means for pressing the seal flange and said first face together to form the joint within the groove. 130

4. A machine for applying flanged seals to interior grooved bottles, comprising a tool, for conforming the seal flange to the groove, having a working face adapted to engage the edge of the flange to confine its circumference, an end below said face having a face for supporting the flange from the inner side thereof, a split ring engaged by said lower end to hold the seal thereon, and means for pressing the flange and said first face together to form the joint within the groove. 65
5. A machine for applying flanged seals to interior grooved bottles, comprising a tool, for conforming the seal flange to the groove, having a working face adapted to engage the edge of the flange to confine its circumference, an end below said face having a face for supporting the flange from the inner side thereof, a split ring engaged by said lower end to hold the seal thereon, and means for reciprocating said receptacle and for pressing the flange and said first face together to form the joint within the groove. 70
6. A machine for applying flanged seals to interior grooved bottles, comprising a tool, for conforming the seal flange to the groove, having a working face adapted to engage the edge of the flange to confine its circumference, a plunger mounted to move within said tool and having a protruding side face for supporting the flange from the inner side thereof and a bottom face to seat upon said seal, means for holding said seal on said plunger, and means for pressing said tool and plunger to said seal to form the joint within the groove. 75
7. A machine for applying flanged seals to interior grooved bottles, comprising a tool, for conforming the seal flange to the groove, comprising a seal flange conforming plunger having means for confining the circumference of the flange, a seal flange spreading plunger mounted to slide within said conforming plunger having an upwardly diverging lower end for spreading the said seal flange, a plunger mounted to slide within said spreading plunger having a protruding side face for engaging the inner face of said seal flange and a bottom face to seat upon said seal, means for holding the seal on said side face, and means for pressing the plungers and seal together to form the joint within the groove. 80
8. A machine for applying flanged seals to interior grooved bottles, comprising a receptacle having a bottle centralizing lower end, a sleeve slidably mounted within said receptacle having a bottle centralizing and holding lower end, a resistance spring backing said sleeve, a seal forming plunger having a working face on its lower end, a depending flange on said end forming a shoulder for coacting with the edge of said seal flange to confine its circumference, a seal flange spreading plunger mounted to slide within said forming plunger having an upwardly diverging lower end for engaging the said seal flange, a plunger mounted to slide within said spreading plunger having a protruding side face for engaging the inner face of said seal flange and a bottom face to seat upon said seal, a groove in said side face, a split ring engaged in said groove to hold the said seal to said side face, and means for reciprocating said receptacle and pressing said sleeve to hold said bottle and said plungers and said seal together within the said bottle to form the said joint. 85
9. A machine for applying flanged seals to interior grooved bottles, comprising a receptacle having a bottle centralizing lower end, a sleeve slidably mounted within said receptacle having a bottle centralizing and holding lower end, a resistance spring backing said sleeve, a seal forming plunger having a working face on its lower end, a depending flange on said end forming a shoulder for coacting with the edge of said seal flange to confine its circumference, a resistance spring behind said forming plunger, a seal flange spreading plunger slidably mounted within said forming plunger, having an upwardly diverging lower end for spreading the said seal flange, a resistance spring behind said spreading plunger, a seating plunger mounted to slide within said spreading plunger having a protruding side face for engaging the inner face of said seal flange and a bottom face to seat upon said seal, a groove in said side face, a split ring engaged in said groove to hold the said seal to said side face, a resistance spring backing said seating plunger, and means for reciprocating said receptacle and compressing said springs to press said sleeve on said bottle and said plungers on said seal within the said bottle to form the said joint. 90
10. In a bottle sealing device for use with a seal having an upturned flange adapted to be formed in a grooved necked bottle to make an air tight joint, a seal forming tool having a lower working end, comprising a depending flange forming a shoulder to confine the circumference of the seal flange, a downwardly extending side wall for supporting the inner face of said seal, and an intermediate upwardly diverging face to spread the outer edge of said seal flange. 100
11. A seal forming tool comprising a spring backed forming plunger having a lower working end formed with a depending flange to form a shoulder to engage the edge of said seal flange to confine its circumference, a spring backed seal flange spreading plunger mounted to slide in said forming plunger and having an upwardly diverging lower end for spreading said seal 105

flange, a spring backed seal seating plunger mounted to slide within said spreading plunger and having a side face to engage the inner face of said seal and a bottom face to seat on said seal, and a split ring mounted

5 within a circumferential groove in said seating plunger to hold in spring pressed en-

gagement a seal when placed on said seating plunger.
